UNITED STATES PATENT OFFICE.

FRANK J. MARRINGTON, OF FORT DODGE, IOWA.

SWITCH FOR SPARKING DEVICES.

1,009,162.

Specification of Letters Patent. Patented Nov. 21, 1911.

Application filed March 6, 1909. Serial No. 481,745.

To all whom it may concern:

Be it known that I, FRANK J. MARRINGTON, a citizen of the United States, residing at Fort Dodge, in the county of Webster and State of Iowa, have invented a certain new and useful Switch for Sparking Devices, of which the following is a specification.

The object of my invention is to provide 10 a switch of simple, durable and inexpensive construction especially designed for use in connection with the sparking devices of explosive engines, whereby a single sparking plug may be used in each cylinder of the 15 engine and current delivered to each plug either by means of a magneto generator or a battery; and, further, to provide a switch of this kind in which the switch may be set to normal position to prevent sparking by 20 either the magneto generator or the battery and at the same time the magneto generator may be operated and the current produced thereby will be short circuited.

My invention consists in the construction, 25 arrangement and combination of the various parts of the device whereby the objects contemplated are attained, as hereinafter more fully set forth, pointed out in my claims, and illustrated in the accompanying drawings, in which—

Figure 1 shows a perspective view of a switch embodying my invention, also the 30 sparking plugs of four engine cylinders, the magneto generator and the battery, and the other devices arranged in the circuits for 35 producing sparks at the proper time. Fig. 2 shows a top or plan view of the switch detached. Fig. 3 shows a side elevation of the switch detached, and Fig. 4 shows a sectional view on the line 4—4 of Fig. 3.

Referring to the accompanying drawings, I have used the reference numeral 10 to indicate the base of the switch. Arranged at the longitudinal center of the switch are 45 five contact pieces indicated by the numeral 11. To four of these contact pieces, I have pivoted a switch blade 12, and to the other, a short switch blade 13. These blades are all connected by means of a top piece 14 50 made of insulating material and provided with a handle 15. When the switch blades are in their normal or disconnected position, as shown in Fig. 1, the under surface of each blade inclines upwardly and outwardly away 55 from the base 10 in both directions, except

for the blade 13 which extends only in one direction from the center.

Arranged at one side of the base 10 are four contact pieces 16 of such size and shape that when the blades 12 have their adjacent ends inclined downwardly, they will rest in the contact pieces 16 and form an electrical connection therewith. Adjacent to the contact pieces 16 is another contact piece 17 to receive the adjacent end of the switch blade 13. Adjacent to the contact piece 17 is a second contact piece 18 for the switch blade 13, which contact piece is so arranged that it will engage and form an electrical connection with the switch blade 13 when the small end of the switch blade 13 is tilted downwardly toward the base 10, and also when it is in a substantially horizontal position, as shown in Fig. 1, but said switch blade 13 will be out of engagement with the contact piece 18 when the pointed end of the switch blade 13 is elevated to its upper limit. On the opposite side of the base 10 are four contact pieces 19 to receive the ends of the switch blades 12 when they are tilted downwardly toward the contact pieces 19.

In Fig. 3 of the drawings, I have shown the means by which the switch blades are connected with the part 14, each blade being provided at its top with a laterally extending portion 20 through which the bolt 21 is passed, said bolt being also extended through the part 14.

In Fig. 4 of the drawings, I have shown the switch, by solid lines, in its normal position, and by dotted lines, tilted to both limits of its movement.

When the switch is in the position shown in Fig. 1, the switch blade 13 establishes electrical connection between the contact piece 11 to which it is pivoted and the contact piece 18. When the switch blades are tilted to one limit of their movement, the blades 12 will form contact between the parts 11 and 16, and the blade 13 will form contact between the parts 11, 17 and 18; and when the switch is tilted to its opposite limit of movement, the blades 12 will form contact with the contact pieces 19.

Referring to Fig. 1 of the drawings, I have used the reference numeral 22 to indicate the engine cylinders of which four are shown in the present instance. In each of the cylinders is a sparking plug 23 of ordinary construction. These four sparking

plugs are connected by the wires 24 with the contact pieces 11 that support the blades 12. The contact piece 11 that supports the blade 13 is connected by means of the wire 25 with 5 the engine cylinder.

I employ two independent electric circuits for the purpose of producing sparks by means of the same sparking plugs. The first circuit comprises a battery 26 electrically connected by the wire 27 with the contact piece 17. The battery 26 is also connected with a circuit breaker 28 by means of the wire 29. The circuit breaker in turn is connected by means of a wire 30 with the 10 primary coil 31 of an induction coil of ordinary construction. This primary coil is electrically connected by the wire 32 with the engine cylinder. A secondary coil of the induction coil is indicated by the numeral 33 and is electrically connected by a wire 34 with the engine cylinder, and is also connected by a wire 35 with a distributor 36 of ordinary construction. This distributor has four wires 37 connected with it, which 15 wires are also connected with the contact pieces 16.

Assuming that the switch blades 12 are in position in engagement with the contact pieces 16, then each time that the circuit 20 breaker is operated a current will be passed from the battery through the circuit breaker to the induction coil and from the secondary coil of the induction coil to the distributor, and by the distributor it will be delivered 25 to the contact pieces 16 and from there will flow through the blades 12 to the contact pieces 11, and from them to the sparking plugs, and inasmuch as both coils of the induction coil are connected to the engine cylinder, 30 the sparking circuit will be thereby completed. Furthermore, the battery is also connected by means of the wire 27 with the contact piece 17 and as this contact piece will be in engagement with the blade 13 and 35 as said blade is connected by the wire 25 with the engine cylinder, the circuit will thereby be completed.

I employ the same sparking plugs and switch to operate in connection with the 40 magneto generator which is diagrammatically illustrated in Fig. 1 and indicated by the numeral 38. The generator shown is of the kind now in general use for automobile ignition and belongs to that type of generators in which the armature has a low 45 tension and a high tension winding. One end of each winding is grounded on the frame and the other ends are arranged as follows: The low tension winding is connected to the brush 40 and the high tension winding to the brush 39. The circuit breaker 42 is connected to the engine cylinder by means of a wire 43. The brush 39 is connected with the distributor 44 by means of 50 the wire 45 and the said distributor has four 55

wires 46 connected with it which lead to the four contact pieces 19 of the switch. The magneto generator is connected by means of a wire 47 with the wire 25 and the brush 40 of the magneto generator is connected by 60 means of a wire 48 with the contact piece 18.

The operation of the device, when working on the magneto generator, is as follows: Assuming the switch to be in the position shown in Fig. 1, then only a low tension circuit will be produced by the generator and this current will be short circuited without passing through the circuit breaker, for the current will flow from the brush 40 through the wire 48 to the contact piece 18 and through the switch blade 13, the contact piece 11 and from thence through the wires 25 and 47 back to the generator frame. When however the switch is set to position with the blades 12 in engagement with the contact pieces 19, then the short circuit 70 through the contact pieces 18, before described, will be broken and the low tension circuit from the brush 40 will flow to the circuit breaker over the wire 41 and when 75 the circuit breaker is in its closed position, as shown in Fig. 1, the current will flow through the wire 43, through the engine frame and return over the wire 47 to the generator. When however the circuit 80 breaker is in its open position a high tension current will be induced in the generator and will flow through the brush 39, through the wire 45 to the distributor and from thence through the wires 46 to the contact pieces 19, then through the switch 85 blades, the contact pieces 11, and from them through the wires 24, the spark plugs, and from the engine frame through the wire 47 90 back to the generator.

I claim as my invention:

1. A switch for sparking purposes comprising a base, a blade movable on the base, two electric contact devices fixed to the base at opposite ends of the blade, and so arranged that the blade, when in one position, will be out of engagement with both of said electric contact devices, and when in other positions, in engagement with either one of said electric contact devices, a second blade 110 operatively connected with the first to move in unison with it, and two electric contact devices for the second blade fixed to the base, one of said electric contact devices for the second blade being arranged to be in 115 contact with its blade when the first mentioned blade is in a neutral position, and also when the first blade is moved to position in engagement with one of its electric contact devices, and the other electric contact device for the second blade being arranged in position to engage the second blade only when the first mentioned blade is in the last mentioned position, for the purposes stated.

2. An electric switch for sparking purposes, comprising a base, a series of supports on said base in line with each other and made of conducting material, a series of blades pivoted to said supports, means for connecting them so that they may be moved in unison, two contact devices for one of said blades, hereinafter referred to as the short blade, arranged on the same side of the pivotal center, the one nearest the center being materially longer than the other so that a contact with said short blade will remain unbroken when the blade is moved out of engagement with the other one of said contact devices, the other blades of the series being extended in opposite directions from the pivotal center, and a series of contact devices fixed to the base, one at each end of each blade so arranged that when the switch is in neutral position all of the blades will be out of engagement with their respective

contact devices except the said long contact device, and when the switch is moved to one limit of its movement both of the contact devices for said short blade will be in engagement therewith and the adjacent ends of the other blades of the series will be in engagement with the contact devices on one side of the base, and when the switch is tilted to its other limit of movement, the opposite ends of the long blades will be in engagement with the other ones of the contact devices, and both of the contact devices for the short blade will be out of engagement with it, substantially as and for the purposes stated.

Des Moines, Iowa, Feb. 15, 1909.

FRANK J. MARRINGTON.
